UNITED STATES PATENT OFFICE.

WILLIAM R. WIDDUP, OF SPARTANBURG, SOUTH CAROLINA, ASSIGNOR OF ONE-THIRD TO EDWARD TANNER AND ONE-THIRD TO THOMAS WOFFORD, BOTH OF SPARTANBURG, SOUTH CAROLINA.

THIN-PLACE PREVENTER FOR LOOMS.

1,116,188.

Specification of Letters Patent.

Patented Nov. 3, 1914.

Application filed September 20, 1912. Serial No. 721,494.

To all whom it may concern:

Be it known that I, WILLIAM R. WIDDUP, a citizen of the United States, residing at Spartanburg, in the county of Spartanburg and State of South Carolina, have invented certain new and useful Improvements in Thin-Place Preventers for Looms, of which the following is a specification.

This invention relates to attachments for looms for weaving, and has for its object to provide simple and effective means for binding the filling against the shuttle box to furnish the loom with a thin-place preventer or filling tension device, by means of which the grid or grate in front of the filling fork may be dispensed with.

The construction of the filling binder or tension made in accord with my invention is such that it will not permit the thread to slip nor will it gather lint, for when the bunter strikes the lay the bunter will have a rolling motion which dislodges any lint preventing an accumulation of lint between the bunter and the shuttle-box, the roll of 25 the bunter also prevents the filling forming a groove in the bunter as the roll tends to keep the bunter smooth.

In applying my invention to looms the back wall of the shuttle-box on the lay is made concave at a point where the bunter engages therewith, the concave portion corresponding as to curvature with the thread engaging face of the bunter.

In the accompanying drawings which illustrate my invention, Figure 1 is a partial plan view of a loom showing my invention applied thereto. Fig. 2 is a side elevation partly in section, and Fig. 3 is a side elevation partly in section of the attachment for the loom.

The loom may be of the ordinary type, and 1 refers to the lay the shuttle-box 2 having its rear wall 3 provided with a concave portion, the concave recess being vertical and 45 formed in the wall of the shuttle-box at a point where the bunter 4 will contact therewith for the purpose of clamping the filling thread 5 against such curved or recessed back wall of the shuttle-box. The vertical

concave recess 6 is located to one side of the filling fork that is carried by the breast beam, which fork may be of the usual construction, and by means of my invention a grate or grid is rendered unnecessary though the same may be used as it will not interfere with the successful operation of my invention.

To the breast beam 7 of the loom, to one side of the support for the weft or filling fork 8, the thin place preventer or filling tension device is applied, the same comprising a base 9 having at one end an upward projecting lug 10 provided with an aperture 11, and at the other end nearest the lay the base has lateral extensions with apertures 12 for the passage of bolts which engage and retain in place a box or guide 12 that is formed to provide at its upper portion a housing 13 for a spring 14. The base 9 has a lateral extending portion 15 that is recessed and extends below the main portion of the base so that its under surface may engage the upper surface of the breast beam to which it is secured by a bolt that passes through a rectangular and elongated slot 16 and engages the breast beam to hold the base in place so as to have a range of adjustment to and from the lay. The construction is such that the base is maintained above the plane of the upper surface of the breast beam and the bolts that secure in place the box or guide will be in advance of the edge of the breast beam nearest to the lay. By maintaining the base 9 so that its end which overlies the breast beam will be above the upper face of the breast beam a space is provided under which the knock-off lever may operate.

The guide-bar 17 which carries the bunter 4, is made of a single piece, except the clamping plate 23 for the bunter 4, and the bar comprises a cylindrical portion 18, having a collar or offset 19 to form a seat for one end of a spring that encircles the portion 18 of the bar 17 and bears against the collar and the lug 10 to force the bunter toward the lay. Beyond the collar 19 the bar is rectangular and is formed to provide

an integral member 20 which extends downward and upon which is formed a head comprising a side piece or cheek 21 that is apertured and countersunk for the passage of a 5 bolt 22 which passes through the bunter 4 and clamps in place a removable cheek piece or plate 23, the bolt either engages with a nut or its threaded portion may engage with a screw threaded aperture in the removable 10 cheek piece. The bunter 4 is preferably made up of three or more pieces of leather each having curved faces for engagement with the thread to provide a bunter that is shaped to conform with the recess 6, in the 15 back wall of the shuttle-box, and the aperture for the passage of the bolt through the bunter may be of larger diameter than the bolt 22 to permit forward adjustment of the bunter should such adjustment be found 20 desirable.

The bar 17 is normally held in line with the upper surface of the base by a plate 24 that has a nib 25 which is overlaid by a part of the spring 14, the construction allowing an oscillating movement of the slideable and spring pressed bar to which the bunter is fixedly attached.

In use when the lay moves forward it strikes the leather bunter and moves the 30 bar 17 back compressing the spring that encircles the cylindrical portion of the bar, and the back movement of the lay is accompanied by a downward movement, which is followed by an oscillatory movement of 35 the bunter which fits the recess 6 which is the segment of a circle, the bar carrying the bunter being maintained so that it may rise and fall and keep the thread 5 which is clamped between the recess and the bunter. 40 The movement of the bunter provided by the construction shown and described obviates and prevents the thread forming a groove in the contacting face of the bunter, as such a groove will allow the thread to 45 slip, the grooving of the bunter being prevented by the rocking or oscillatory motion which is given to the bunter by contact of the lay therewith and the rocking or oscillatory motion keeps the bunter free from 50 lint.

With the device shown and described the grate or grid carried by the breast beam opposite the filling fork is dispensed with for the bunter binds the thread against the 55 back of the shuttle-box and as no grate or grid is used there is nothing in the path of the filling fork to touch and this will prevent making a thin place in the fabric, and should the filling of the bobbin be 60 tangled and leave a long end from the shuttle the device will break the same off and obviate a thin place.

By providing the back wall of the shuttle box with a recess and the bunter with

a rounded face I am able to have a rigid 65 supporting bar for the head, and the requisite movement for proper operation is provided for by attaching the bar to the base so that it not only has a sliding movement but also an oscillatory movement when 70 the bunter is engaged by the lay. The construction of the base whereby there is provided a laterally extending and apertured portion provides means whereby the base 75 can be attached to the breast beam by the same bolt that holds the stand or guide for the slide of the filling detector or fork in place, and by providing for a vertical oscillatory movement of the rod carrying the bunter as well as a sliding movement it is 80 unnecessary to provide a joint between the bunter and the rod.

I am aware that prior to my invention that it has been proposed to provide a filling tension device for looms with a grid or 85 grate having a straight vertical recess to one side of the same in which the thread from the shuttle is pressed and held by a resilient finger that is overlaid by a pad, such finger being carried by the slide which 90 also carries the filling detector or fork, and also that it is not new to provide a pivoted bunter that engages with the rear wall of the shuttle box adjacent to the recess that is opposite the filling fork. 95

I claim.

1. The combination in a loom of the lay and its shuttle-box the shuttle-box having a vertically disposed concave recess formed in its back wall to one side of the filling fork, a breast beam to which is rigidly attached a frame one end thereof having an upward projecting lug with an aperture therethrough, a guide-box on the opposite end of the frame from the apertured lug said 100 guide box comprising upward extending sides and a top shaped to house a spring, a presser plate maintained between the sides of the housing and provided with an upward projecting nib, a spring which encircles the nib and bears against the inner side of the transverse portion of the housing, a bar maintained by the frame, a spring on the bar to engage with a part thereof and with the frame; whereby the bar may slide 105 and have a vertical oscillatory movement in the frame when moved by the breast beam to contact with the shuttle-box of the loom, and a bunter having a curved face for engagement with the filling thread between 110 the shuttle and the filling fork.

2. In a loom, a lay provided with a shuttle-box having a concave recess in its rear wall, a support which is fixedly attached to the breast beam of the loom and has at one 115 end an upward extending portion provided with an aperture therethrough and at the other end with a housing having side walls

and a spring actuated presser-plate, a bar carried by the support, a collar on the bar, a spring which engages with the support and with the collar on the bar, for moving the bar toward the lay, a bunter fixedly attached to the bar and provided with a convex face and means for maintaining the bar

so that it may have a vertical oscillatory movement when the bunter engages with the shuttle-box.
